UNITED STATES PATENT OFFICE.

CHARLES PETERSEN, OF SAN FRANCISCO, CALIFORNIA.

STREET-CAR.

1,097,766.

Specification of Letters Patent.

Patented May 26, 1914.

Application filed July 3, 1913. Serial No. 777,186.

To all whom it may concern:

Be it known that I, CHARLES PETERSEN, a subject of the King of Denmark, residing at San Francisco, in the county of San Francisco and State of California, have invented 5 certain new and useful Improvements in Street-Cars, of which the following is a specification.

My invention relates to a street car, and 10 especially to a new and novel arrangement of seats and running boards in connection therewith.

The object of my invention is to provide 15 or construct a car that will have a much larger seating capacity than the cars in common use and still remain within the present recognized standard as to dimensions and general design.

Other objects than the above will be apparent to those skilled in the art, and need not be specifically set forth herein.

I accomplish the above objects by a preferred form of my invention illustrated in the following views.

25 Figure 1 is a vertical fragmentary section through one side of a street car embodying my invention; Fig. 2 is a portion of Fig. 1 showing the lower seat and running-board in its operative or occupied position; Fig. 3 30 is an enlarged detail taken at right angles to Fig. 1, of the central connection of the running board operating device, and—Fig. 4 is an enlarged fragmental perspective view of one forward corner of a seat, showing 35 the recess in which the upper end of said running board operating device is adapted to travel.

Similar reference characters refer to similar parts throughout the several views.

40 The reference character 5 designates substantially the upper portion or body of a street car, having the usual row of seats 5^a extending longitudinally on each side thereof, and a floor 5^b, transverse floor beams 5^c, 45 and the usual car frame 5^d, to which is secured on laterally disposed cross members 5^e, spaced at intervals for the entire length of the car. Instead of having the sides of the car entirely inclosed as is the custom, 50 they are left practically open from the sill of the window 5^h down to the frame 5^e, and vertical ribs 6, extend from said sill down past the ends of the frame members 5^e, to which they are secured at 5^f, and for a short 55 distance below the latter.

The space below the main seats 5^a in most

cars has heretofore been wasted, and it is my desire to utilize this space by installing therein, seats facing outward, which will rest upon the upper edge of the beams or members 5^e, and the backs of said seats will be that part of the car frame 5^d, which supports said upper seats 5^a. The lower seats, however, will be made individually, that is, in sections, a trifle wider than the space between the members 5^e, so that when occupied, they will rest upon the upper edge of said members. Said seats are composed of the two side irons 7, and boards 7^a secured thereto, and said seats are pivoted or hinged 60 at their rear edge to the lower edge of the partition 5^g. The irons 7 are provided with extensions 7^c, at the outer ends of which are secured one end of coiled springs 8, the other end of said spring being secured forwardly of said extensions 7^c, and to the members 5^e, as at 8^a.

9 represents a vertical partition or guard extending the length of the car, suitably secured to the uprights 6, and extending 80 downwardly from the said cross member 5^e, to the lower end of said members 6. At the lower front edge of said partition 9 is hinged at 10, a foot board or running board 11, having the right angle bend 11^a along its 85 rear edge. The following levers connect the seats with said running board 11. On the right-hand side or edge of the seat the side iron 7 is provided with a groove 7^a, in which slides a lug 12^a, on the upper end of a vertical rod 12. Said rod extends down along the inner edge of the upright 6, is pivoted at 12^b to one end of a rocker arm 13, which in turn is centrally pivoted at 13^a to a cross member 6^a, secured between the 90 members 6. Pivoted at 14^a, to the opposite end of said rocker arm 13, and extending downwardly therefrom, is a rod 14, the lower end of which is enlarged as at 14^b, and is provided with a transverse slot 14^c, 100 through which protrudes a lug 11^b on the right angled bend 11^a of the running board 11.

The operation is as follows:—As shown in Fig. 1, the contraction of the spring 8 105 pulls the seat upwardly and the foot board is folded up out of way. When the seat is in operative position, as shown in Fig. 2, it is held down against the tension of said spring 8 by the weight of the occupant thus 110 pushing the rod 12 down, rocking the arm 13 and thereby pulling up the rod 14, which

will cause the lug 11^b to slide in the slot 14^c, and rotate the foot board 11 on its pivotal point 10, and as soon as the occupant leaves the seat, the contraction of the spring 8 thus released, will reverse the movement of the board 11 and restore it and the seat 7 to their inoperative positions.

Having thus described my invention, what I claim as new and desire to secure by Letters Patent, is:—

1. In a street car, in combination with a series of fixed seats, auxiliary seats located below said fixed seats and facing outward, a foot board hinged on said car below said auxiliary seats, and means whereby the forcing down of said auxiliary seats will effectuate the moving of said foot board into operative position.

2. In a street car, in combination with a longitudinally disposed row of main seats, a row of auxiliary seats located below said first seats, and facing outward, foot boards hinged to said car below said auxiliary seats, and means whereby said seats and foot boards will be moved to inoperative position when the seats are unoccupied and to operative position when occupied.

3. In a street car, in combination with a longitudinally disposed row of main seats, a row of auxiliary seats located below said

first seats and facing outward, a foot board located one below each of said auxiliary seats and hinged to said car, a vertical rod, at the upper end of which is a lug adapted to slide in a groove in the side of each auxiliary seat respectively, a rocker arm centrally pivoted to the frame of said car, one end of which is pivoted to the lower end of said vertical rod, a second vertical rod pivoted to the other end of said rocker arm 40 and extending downwardly therefrom, the bottom of said last rod being enlarged and provided with a horizontally disposed slot, a pin permanently secured to the rear and upwardly extending edge of said foot board 45 and adapted to slide in last said horizontally disposed slot, and a spring, one end of which is secured to an extension from the bottom rear edge of each of said auxiliary seats respectively, and the other end is 50 secured forwardly thereof and to the frame of said car.

In testimony whereof I affix my signature in the presence of two witnesses.

CHARLES PETERSEN.
